(57) CLAIM

The ornamental design for a strap force distributor for box trailer edge, as shown and described.

DESCRIPTION

FIG. 1 is a perspective view of the design, showing a top, a front and a left-hand side of the design;

FIG. 2 is a front elevational view of the design;

FIG. 3 is a left side elevational view of the design;

FIG. 4 is a right side elevational view of the design;

FIG. 5 is a top plan view of the design; and,

FIG. 6 is a bottom plan view of the design.

The breaks in the drawing figures show no specific length.
